US0D1026328S

(12) **United States Design Patent** (10) **Patent No.:** **US D1,026,328 S**
(45) **Date of Patent:** **** May 7, 2024**

(54) **FOOT CALLUS REMOVER**

(71) Applicant: **Xiaoxiang Dong**, Hubei (CN)

(72) Inventor: **Zhuxiang Zheng**, Hubei (CN)

(73) Assignee: **Xiaoxiang Dong**, Hubei (CN)

(**) Term: **15 Years**

(21) Appl. No.: **29/882,298**

(22) Filed: **Jan. 12, 2023**

(30) **Foreign Application Priority Data**

Nov. 21, 2022 (CN) 202230774708.8

(51) **LOC (14) Cl.** **28-03**

(52) **U.S. Cl.**

USPC **D28/59**

(58) **Field of Classification Search**

(57) **CLAIM**

The ornamental design for a foot callus remover, as shown and described.

DESCRIPTION

FIG. 1 is a front, right and top perspective view of a foot callus remover, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the foot callus remover that form no part of the claimed design.

1 Claim, 8 Drawing Sheets
